DESIGN FOR A LIQUID DISPENSER

Walter C. McHenry, Oakland, Calif., assignor to
Buttermilk Dispensers, San Francisco, Calif.,
a partnership composed of Calvin C. Chap-
man, (limited partner) Louis G. Kaskey and
Charles E. Gibbs (general partners)

Substituted for abandoned application Serial
No. D-70,107, June 29, 1937. This applica-
tion October 11, 1937, Serial No. 72,119

Term of patent 14 years

To all whom it may concern:

Be it known that I, Walter C. McHenry, a citizen of the United States, residing in the city of Oakland, county of Alameda, State of California, have invented a new, original, and ornamental Design for a Liquid Dispenser, of which the following is a specification, reference being had to the accompanying drawing forming part thereof.

This application is a substitute for Serial No. D-70,107.

Fig. 1 is a front elevational view of the liquid dispenser showing my new design;

Fig. 2 is a side elevation;

Fig. 3 is a rear elevation; and

Fig. 4 is a fragmentary top plan view.

I claim:

The ornamental design for a liquid dispenser, substantially as shown.

WALTER C. McHENRY.
